2,448,275

NITRILE-PRODUCING METHOD

Ralph H. Potts, La Grange, Ill., assignor to
Armour and Company, Chicago, Ill., a corpora-
tion of Illinois

Application June 29, 1945, Serial No. 602,220

8 Claims. (Cl. 260—465.2)

1

This invention relates to a nitrile-producing method and apparatus, and is particularly useful in the manufacture of nitriles, etc., from fatty acids.

An object of the invention is to provide a method and apparatus in which a product considerably higher in nitrile content is produced, while at the same time eliminating the necessity of redistilling the bottoms or residues, as required in prior practice. A further object is to provide apparatus and process in which pitch will be produced as a finished product without the necessity of redistillation as heretofore found necessary. A further object is to provide a continuous liquid-phase process in which stripped fatty acid residues are reacted with fresh or recycled ammonia and in which the ammonia vapors evolved are utilized for stripping incoming fatty acid charging stock. Other specific objects and advantages will appear as the specification proceeds.

The invention is illustrated in a preferred embodiment, by the accompanying drawing, which shows in elevation diagrammatical apparatus embodying my invention and illustrating my process.

In the illustration given, fatty acid charging stock is introduced through line 10 into the heater 11 in which any suitable heating medium, such as, for example, Dowtherm, may be employed for drying the stock. Preferably, flow-control apparatus 10a, which per se is of well-known construction, is employed to maintain a constant rate of flow through line 10. From the heater, the fatty acids which have been preheated pass through line 12 to a reaction tower 13 in which the fatty acids are brought into contact with ammonia and nitrile vapors. The reaction tower 13 is provided with an overhead outlet line 14 leading to the condenser 15. Nitrile vapors, ammonia, water of reaction, and some fatty acids will distill upwardly through the tower and be condensed in condenser 15. Part of the condensed material will pass through line 18 to the heater 19, while a portion of the material will pass as reflux through line 16 to the tower, forcing the higher boiling fatty acid material downwardly through the tower to the heater 17 at the base of the tower. The heater 17 shown in the drawing is of the Callandria type employing Dowtherm as a heating medium. Other types of heaters using any suitable heating medium may be employed. The heater 17 brings the material to a temperature suitable for liquid phase reaction of the fatty acids and ammonia (about 575°—625° F. for most charging stocks). A residue withdrawal line 20 leads from

the base of tower 13 and enters the upper portion of a second reaction tower 21.

The tower 13 is provided with trays or pans, as indicated in the drawing by dotted lines 13a, and gaseous ammonia passing upwardly in the tower comes successively into contact with liquid fatty acids on these trays to complete the liquid phase reaction and produce the nitrile product. The ratio of nitriles to fatty acids becomes progressively greater toward the top of the tower.

As illustrated diagrammatically, means are provided for automatically maintaining a level of high boiling fatty acid residue in the lower portion of tower 13. Valve mechanism 22 is controlled by electric mechanism of well-known construction (per se), actuated by a level control 23 in the lower portion of tower 13. By this means, a predetermined level is maintained in the tower.

Reaction tower 21 may be of any suitable construction. In the illustration given, it is shown provided with an overhead vapor line 24 through which ammonia, nitrile vapors, and fatty acids pass into the lower portion of the pool maintained in the base of tower 13. Heated ammonia is passed into the base of tower 21 through line 25. A residual line 26 leads from the base of tower 21 and is employed for the withdrawal of pitch which may be intermittent or continuous. In the structure shown, I provide a valve 27 which is electrically operated to control the withdrawal of pitch in accordance with a level control device 28 at the lower portion of tower 21.

Tower 21 may be provided with the trays 21a indicated by dotted lines in the drawing. These trays contain a certain amount of liquid fatty acids, and the gaseous ammonia passing upwardly in large volume comes successively into contact with the liquid on each tray. The ammonia serves to carry the fatty acids upwardly, separating them from the pitch, and also reacts with the acids to some extent to produce an appreciable amount of nitriles in this tower.

The material passing from condenser 15 through line 18 preferably is heated to a temperature suitable for vapor phase reaction of the fatty acids and ammonia (600°—700° F. for most stocks) in heater 19 and is then passed through one of the catalyst chambers 29 and 30. Catalyst chamber 29 has tubes 29a in which is held a suitable dehydrating catalyst, such as nickel, and chamber 30 has similar tubes 30a. The catalyst chambers may be of any suitable construction. They are shown each provided with heating lines 31 through which Dowtherm or other heating fluid may be passed into the chambers about the tubes

29^a and 30^a. Lines 32 may be employed for introducing steam and air into the catalyst chambers for the purpose of regeneration of the catalyst, and valve-controlled vents 32^a permit the escape of steam and air.

From the catalyst chambers, the material passes through line 33 into a stripping tower 34 having bubble pans or plates with a series of vertically-spaced drawoff outlets 35. Water may be withdrawn, together with impurities, from one of the intermediate pans, while, if desired, an ammonia solution may be drawn off from one of the upper pans. The overhead vapors pass out through line 36 and are condensed in condenser 37, the condensate being returned through line 38 to the upper portion of the stripping tower. The uncondensed ammonia is returned through line 39 and may be reused by passing it through line 40 and heater 41 from which it enters the reaction tower 21 through pipe 25.

Additional ammonia to make up the deficiency in line 39 may be introduced through line 39^a. Such ammonia preferably passes through a steam heater 39^b. While valves are provided for hand control of line 39^a, I prefer to employ an automatic flow-control device 39^c of the orifice-plate-air-line-valve type, which is of well-known construction per se, and which maintains a constant rate of flow through line 40.

Heretofore it has been the practice to redistill stripped fatty acid residues with the aid of steam to form a finished pitch product, this step being a separate operation. In the present process, the pitch is recovered as a finished product at the base of the second tower and without any further treatment, while at the same time an increase in nitrile content of the stripped vapors is accomplished in the second tower. A pool of high boiling fatty acid material is maintained in the base of the first tower, and it is into the lower portion of this pool that the evolved vapors from the second tower are introduced. Thus, the incoming fatty acid is first encountered in the reaction chamber 13 above the liquid pool by the gaseous ammonia from the second tower; then the stripped residue while in the pool at the base of the tower is again subjected to such vapors; and finally in the second tower the stripped material undergoes a further reaction and stripping operation, meeting in the base portion of the tower the fresh ammonia entering the tower. The entering ammonia passes into a pool of higher boiling fatty acid residue and pitch is substantially continuously withdrawn through the outlet pipe 26. The towers 13 and 21 are preferably operated at atmospheric pressure or slightly above.

In the second tower 21, the stripping action is unusually effective because the ratio of molecules of ammonia to molecules of fatty acid is very sharply increased and therefore the partial pressure of the fatty acid is much lower, thus allowing it to distill at a lower boiling point. There is also more mechanical action as a result of the increased agitation. The chemical relationship is also improved because the mass effect of the large ratio of ammonia to fatty acids in the second tower drives the chemical reaction in the desired direction toward nitrile formation.

While in the foregoing specification, I have set forth certain details of operation and specified certain apparatus, it will be understood that such details and apparatus structures are set forth for the purpose of explaining the invention and the same may be varied widely by those skilled in the

75

art without departing from the spirit of my invention.

I claim:

1. In a nitrile-producing process, the steps of maintaining two ammonia-fatty-acid reaction zones, passing fatty acids into the first of said zones, heating said acids in said zone to a liquid phase reaction temperature, contacting the same with ammonia vapors evolved from the second of said zones, passing high boiling fatty acid residue from said first zone to said second zone, contacting the same in said second zone with ammonia vapors, and withdrawing the stripped high boiling residue as pitch from said second zone.
2. In a nitrile-producing process, the steps of maintaining two ammonia-fatty-acid reaction zones, passing fatty acids into the first of said zones, contacting the same with nitrile and ammonia vapors evolved from the second of said zones, maintaining in said first zone a pool of high boiling fatty acid material, heating said pool to a liquid phase reaction temperature, passing material from said pool to said second zone, contacting the same in said second zone with ammonia vapors, and withdrawing the stripped high boiling residue as pitch from said second zone.
3. In a nitrile-producing process, the steps of maintaining two ammonia-fatty-acid reaction zones, passing fatty acids into the first of said zones, heating said acids to a liquid phase reaction temperature, contacting said acids with ammonia vapors evolved from the second of said zones, passing high boiling fatty acid residue from said first zone to said second zone, maintaining a pool of high boiling fatty acid residue in said second zone, introducing ammonia into said pool of residue, and withdrawing stripped high boiling residue as pitch from said second zone.
4. In a nitrile-producing process, the steps of maintaining two ammonia-fatty-acid reaction zones, passing fatty acids into the first of said zones, heating said acids to a liquid phase reaction temperature, contacting said acids with ammonia vapors evolved from the second of said zones, maintaining a pool of high boiling fatty acid residue in said first zone, passing residue from said pool to said second zone and contacting the same in said second zone with ammonia vapors, maintaining a pool of high boiling fatty acid residue in said second zone, introducing ammonia into said pool, and withdrawing stripped high boiling residue as pitch from said pool in said second zone.
5. In a nitrile-producing process, the steps of maintaining two ammonia-fatty-acid reaction zones, passing fatty acids into the first of said zones, heating said fatty acids to a liquid phase reaction temperature, contacting the same with ammonia vapors evolved from the second of said zones, passing high boiling fatty acid residue from said first zone to said second zone, withdrawing nitrile, ammonia, and water vapors from said first zone, separating the ammonia, returning the ammonia to said second zone, contacting the residue in said second zone with said returned ammonia, and withdrawing the stripped high-boiling residue as pitch from said second zone.
6. In a nitrile-producing process, the steps of maintaining two ammonia-fatty-acid reaction zones, passing fatty acids into the first of said zones, heating said fatty acids to a liquid phase reaction temperature, contacting the same with ammonia vapors evolved from the second of said zones, passing high boiling fatty acid residue

from said first zone to said second zone, contacting the same in said second zone with ammonia vapors, maintaining a pool of high boiling fatty acid residue in said second zone, withdrawing nitrile, ammonia, and water vapors from said first zone, separating the ammonia, returning the ammonia at elevated temperatures to the pool in said second zone, contacting the residue in said second zone with said returned ammonia, and withdrawing the stripped high-boiling residue as pitch from said second zone.

7. In a liquid phase nitrile-producing process, the steps of maintaining two ammonia-fatty-acid reaction zones, passing fatty acids into the first of said zones, heating said acids therein to liquid phase reaction temperature, contacting the same with ammonia vapors evolved from the second of said zones, passing high boiling fatty acid residue from said first zone to said second zone, introducing into said second zone in contact with said fatty acid residue, the bulk of the ammonia required for the reaction in the two zones, contacting said high-boiling fatty acid residue in said second zone with said ammonia to strip said high-boiling fatty acid residue, and withdrawing the stripped high boiling residue from said second zone.

8. In a nitrile-producing process, the steps of maintaining two ammonia-fatty-acid reaction zones, passing fatty acids into the first of said zones, heating said acids in said zone to a liquid phase reaction temperature, contacting the same with ammonia vapors evolved from the second of

5 said zones, passing high boiling fatty acid residue through said first zone to said second zone, contacting the same in said second zone with ammonia vapors in quantities sufficient to reduce the high boiling residue to pitch, and withdrawing pitch from said second zone.
